UNITED STATES PATENT OFFICE.

JULIUS KUHNERT, OF BRESLAU, GERMANY.

DRILL-SHARE.

1,080,012.

Specification of Letters Patent.

Patented Dec. 2, 1913.

Application filed February 14, 1913. Serial No. 748,426.

To all whom it may concern:

Be it known that I, JULIUS KUHNERT, a subject of the German Emperor, and resident of Breslau, Germany, have invented 5 certain new and useful Improvements in Drill-Shares, of which the following is a specification.

This invention relates to improvements in drill shares, and more particularly to a device for an easily disengageable attachment 10 of the pressure rollers to drill shares, which can easily be applied to already used, old machines without necessitating an essential alteration of the same.

15 The device consists of a stay, which closes the front end of the roller supporting strap and which is provided with grooves for engagement with the diverging draw-bars of the drill share and with a rearwardly directed wedge engaging the angle formed by 20 the bars, the latter being thus adapted to be removably secured to the stay by means of an ordinary screw-joint.

The accompanying drawing shows the im- 25 proved arrangement.

Figure 1 is a longitudinal section through the device on the line A—A of Fig. 2 which is a plan view of the same, Fig. 3 is a plan view of the connection-stay on a larger 30 scale, and Fig. 4 a cross section through the attachment, on the line B—B of Fig. 2, also on a larger scale.

α is the pressure-roller, of which the sup-

porting strap b is at the front closed by a stay c.

d is the drill share with its diverging draw-bars e. For connecting the strap with the draw-bars, the stay c is provided at one end with grooves c¹ for engagement with the bars, and at the other end with a rearwardly directed wedge c² which engages the angle formed by the bars, so that the parts, which are thus already firmly connected, can be secured to each other by a screw-joint f of ordinary type.

What I claim is:

A device for a disengageable attachment of pressure-rollers to drill shares, comprising in combination, a roller supporting strap, a stay to close the front end of the latter provided at one end with grooves, diverging draw-bars for the drill share designed to engage said grooves, a rearwardly directed wedge at the other end of the stay engaging the angle formed by the draw- 55 bars, and a screw-joint of ordinary type, to connect all said parts together, substantially as and for the purpose set forth.

In testimony whereof I have hereunto set my hand in the presence of two subscribing 60 witnesses.

JULIUS KUHNERT.
